UNITED STATES PATENT OFFICE

GOTTFRIED NIEBEL, OF NEW YORK, N. Y.

DESIGN FOR AN ELECTRIC BULB OR SIMILAR ARTICLE

Application filed November 30, 1929. Serial No. 33,593. Term of patent 14 years.

To all whom it may concern:

Be it known that I, GOTTFRIED NIEBEL, a citizen of the United States, and resident of 419 West 115th Street, in the city of New York, in the county of New York, and State of New York, have invented a certain new, original, and ornamental Design for an Electric Bulb or similar article, of which the following is a specification, reference being had to the accompanying drawing, forming part thereof.

Fig. 1 is an elevational view of an electric bulb showing my new design; and

Fig. 2 is a cross sectional view of the electric bulb shown in Fig. 1.

Fig. 3 shows a somewhat enlarged detail of a portion of the surface of the electric bulb upon which the raised elements are shown.

I claim:

The ornamental design for an electric bulb or similar article substantially as shown, and described.

Signed at New York, in the county of New York and State of New York this eighteenth day of November, A. D. 1929.

GOTTFRIED NIEBEL.
